UNITED STATES PATENT OFFICE

2,526,167

SLIDABLE JAW PIPE WRENCH

Warren A. Sparks, Long Beach, Calif., assignor
to John M. Henry, Inglewood, Calif.

Application April 26, 1948, Serial No. 23,165

2 Claims. (Cl. 81—174)

1

This invention relates to a wrench, and more particularly a pipe wrench in which means is provided for rapidly setting the wrench in work engaging position and releasably holding the wrench in such work engaging position simply by the rotation of the handle member.

It is a feature of this invention that when the jaw is adjusted to the accommodation of larger size pipe, which is generally accompanied with greater resistance to the making up of a pipe joint, the length of the handle of the wrench is correspondingly increased with a corresponding increase in mechanical advantage, thus tending to overcome the increased resistance.

It is a further feature of this invention that while a conventional pivoted cam jaw member is utilized, the disadvantages attending the carrying of the load upon the pivot pin of such jaw member are overcome by carrying the load directly on the socket of the cam.

It is a further feature of this invention that work engaged by the wrench is automatically centered in the jaws, thus distributing the load equally over the circular socket of the pivoted jaw.

It is, accordingly, one object of this invention to provide a pipe wrench of the type described in which the length of the handle, and, correspondingly, the mechanical advantage, is increased when the wrench is adjusted to accommodate larger pipe.

It is a further object of this invention to provide a wrench of the type described which is quickly adjusted to the size pipe and held in such adjustment by a rotation of the handle member.

It is a further object of this invention to provide a wrench of the type described having a pivoted jaw member in which means is provided for removing the load from the jaw pivot pin.

These and further objects and advantages will be apparent from the annexed specification in which:

Figure 1 is a side elevation of a pipe wrench embodying the present invention;

Figure 2 is a bottom view, partly in section, of the wrench shown in Figure 1;

Figure 3 is a section taken along the line 3—3 of Figure 2;

Figure 4 is a section taken along the line 4—4 of Figure 3;

Figure 5 is a section taken along the line 5—5 of Figure 3; and

Figure 6 is a section taken along the line 6—6 of Figure 3.

2

Referring now more particularly to the drawings, there is shown a wrench indicated generally at 10 and including a main bar 11 having a flattened mandrel portion 12 threaded on its outer end as at 13 to receive a sleeve handle member 14 which is internally threaded as at 15 for engagement with the threads 13 of the mandrel. The handle member 14 may be provided with a plurality of knurled rings 16 to facilitate gripping by the operator. The main bar member 11 is recessed on either side as at 17 and is provided with a central opening or slot 18 which is bridged as at 19 and 20 as indicated in Figure 3.

A slide 21 comprising a generally cylindrical member split into two halves 22 and 23 is mounted upon the main bar member forward of the handle member 14 and the two halves are held together by pins 24, 25 and 26. The two halves 22 and 23 are provided at their inner sides with keys 27 and 28 adapted to ride in the recesses 17 or the slot 18 and thus maintain the slide 21 in position upon the bar 11. A coil spring 29 is provided between the two halves 22 and 23 of the slide 21 with one end abutting the pin 26 and the other end abutting the bridge 19 thus tending to bias the slide 21 toward the rear of the wrench. The pin 25 is adapted to engage the forward side of the bridge 19 and provide a stop preventing the slide 21 from moving rearward of the wrench further than is desired under the bias of the spring 29. The two halves 22 and 23 of the slide 21 are each provided with a V-shaped open jaw member 30 and 31. The bar 11 includes an upstanding rib 32 having an open gap 33 and a forward depending portion 34 in which is pivotally mounted, as by the pin 35, a jaw cam 36. The jaw cam 36 is formed in two identical parts 37 and 38 each carried on the pin 35 and keyed thereto, and a pin 39 is also secured to each of the parts 37 and 38. The forward portion 34 of the bar 11 is recessed on either side as at 40 and 41 to provide sockets for the cams 37 and 38 and thus forming a central portion 42 between the two cams 37 and 38, and the central portion 42 has a shoulder 43 thereon forming a stop adapted to be engaged by the pin 39 and limit rotation of the cam members 37 and 38. Cam members 37 and 38 on their rearward faces are cut on a curve generally approaching a portion of an ellipse, and this portion is serrated as at 44 and 45 to provide a gripping surface.

In operation the wrench 10 is placed upon the work to be engaged, such as a pipe to be turned, with the gap 33 engaging the pipe. The operator may then grasp the slide 21 in one hand and

the handle 14 in the other hand may slide forward until the jaws 30 and 31 are in firm engagement with the pipe and then quickly spin the handle 14 upon the mandrel 12 thus holding the jaws in clamped position. Due to the V-shaped nature of the jaws 30 and 31 and the pivotal mounting of the jaw cams 37 and 38, any pipe engaged by the wrench will be automatically centered in the jaws and the load will be carried by the circular portions 42 forming the defining wall of the recessed sockets 40 and 41 rather than by the pin 35.

It will be apparent from the foregoing that alternatively to quickly adjusting the wrench by sliding the slide 21 forward and then spinning the handle 14 with the other hand, the wrench may be adjusted entirely with the use of only one hand by simply turning the handle 14 to force the slide 21 forward to the desired position. Further, it will be apparent that as the slide 21 is moved rearward to open up the jaws to engage a larger pipe it is necessary to back off the handle 14 thus increasing the over-all length of the wrench and the mechanical advantage available to the operator.

While there has been described what is at present considered a preferred embodiment of the present invention, it will be apparent that various changes and modifications may be made without departing from the essence of the invention, and it is intended to cover herein all such changes and modifications as come within the true spirit and scope of the appended claims.

What is claimed is:

1. A pipe wrench comprising a main bar; said bar being shaped to form a slot on either side of said bar and extending longitudinally thereof; means forming an opening through said bar aligned with said slots; a slide comprising two

parts joined together by pins adapted to project through said opening in said bar and each having a longitudinally disposed key fitting in freely slidable engagement with one of said slots; a jaw carried by the free end of each of said parts; said bar being externally threaded at one end; a handle internally threaded for engagement with the threads on said bar and having a portion adapted to engage the other end of said parts to hold said jaws in work-holding position; said bar having a jaw formed upon its free end spaced from the jaws carried by said parts.

2. A pipe wrench as set forth in claim 1 in which a coil compression spring is provided in said opening having one end engaging a wall of said opening and the other end engaging one of said pins and normally biasing said slide towards open position.
